RAILWAY SWITCH CIRCUIT CONTROLLER

Herbert L. Bone, Swissvale, Pa., assignor to The Union Switch & Signal Company, Swissvale, Pa., a corporation of Pennsylvania

Application January 16, 1933, Serial No. 651,933

9 Claims. (Cl. 246—253)

My invention relates to railway switch circuit controllers.

Circuit controllers embodying my invention are particularly suitable for, although in no way limited to, use in connection with spring switches of the type which are provided with a facing point lock so constructed that when the switch points occupy their normal positions, the locking plunger of the lock will normally occupy a locking position, but that when a train trails the switch the locking plunger will be automatically withdrawn from its locking position to unlock the switch by means mechanically actuated by the train, and that when the movable rails have been returned to their normal positions upon completion of the trailing movement, the locking plunger will be automatically restored to its locking position by spring means to relock the switch.

One object of my invention is to provide means for detecting improper adjustment or operation of the lock in a spring switch of the type described.

Another object of my invention is to provide a latching mechanism for latching the point detector contacts open until they are manually released in the event that the switch points fail to become unlocked in the normal manner while a train is trailing the switch.

Specifically, circuit controllers embodying my invention are an improvement upon the circuit controller described in my copending application for Letters Patent of the United States, Serial No. 620,421, filed July 1, 1932, for Railway switch operating apparatus which has matured into Patent No. 1,976,827, dated October 15, 1934.

I will describe one form of circuit controller embodying my invention, and will then point out the novel features thereof in claims.

In the accompanying drawings, Fig. 1 is a top plan view showing a spring switch A controlled by a switch operating mechanism B provided with a circuit controller E constructed in accordance with my invention. Fig. 2 is an enlarged transverse sectional view of the spring connecting rod C forming part of the apparatus illustrated in Fig.

1. Fig. 3 is an enlarged top plan view of the switch operating mechanism B and the circuit controller E shown in Fig. 1, with the various covers removed to better illustrate the various details of construction. Figs. 4, 5, 6, 7, and 8 are detail sectional views taken substantially on the lines IV—IV, V—V, VI—VI, VII—VII, and VIII—VIII of Fig. 3, respectively.

Similar reference characters refer to similar parts in each of the several views.

Referring first to Fig. 1, the reference character A designates a railway switch comprising, as usual, two fixed rails 1 and 1^a and two movable rails 2 and 2^a. The fixed rails 1 and 1^a are laid on tie plates 3 and are secured to crossties 4 in the usual manner. The movable rails 2 and 2^a are fastened together by a front rod 5, a head rod 6, a bridle rod 7, and a tie rod 8, and may be moved into a normal or a reverse position by means of a switch operating mechanism B which is connected with the head rod 6 through the medium of an operating rod 9 and a spring connecting rod C. When the switch occupies its normal position in which position it is shown in Fig. 1, the movable rail 2 engages the fixed rail 1, and the movable rail 2^a is spaced a slight distance from the fixed rail 1^a. When the switch is reversed, however, the movable rail 2^a then engages the fixed rail 1^a, and the movable rail 2 is spaced from the fixed rail 1.

The spring connecting rod C may have any suitable form, but in the well known form here illustrated, this connecting rod comprises a cylindrical housing 10 having a lateral extension 10^a fastened to the head rod 6 (see Fig. 2). The lower end 10^b of the housing 10 has a smaller diameter than the body of the housing, while the upper end is threaded to receive a cap 11 having an end 11^a similar to the end at 10^b. Slidably mounted in the opening in the end 10^b is a sleeve 12 provided with an annular flange 12^a located within the housing 10, and similarly mounted in the opening in the end 11^a is a sleeve 13 provided with an annular flange 13^a which is also located within the housing 10. A spring rod 14 extends through the sleeves 12 and 13 with sufficient clearness to permit the rod to slide freely in the sleeves, and this rod carries a compression spring 15 which engages the sleeves at their annular flanges and urges the sleeves toward the positions in which the annular flange 12^a of the sleeve 12 engages the shoulder formed on the inside of the housing 10 by the end 10^b, and the annular flange 13^a of the sleeve 13 engages the shoulder formed on the inside of the cap 11 by the end 11^a. The spring rod 14 is provided with an annular shoulder 16 for at times engaging the outer end of the sleeve 12 and with a nut 17 for at times engaging the outer end of the sleeve 13. The lower end of the spring rod 14 is pivotally attached to the operating rod 9. The operation of the spring connecting rod C is well understood and need not, therefore be described here.

The head rod 6 is also connected by means of an adjustable link 49 with the piston rod 50 of a

buffing device D. This buffing device may be of any suitable type but, as here shown, this buffing device is similar in all respects to the buffing device shown and described in Letters Patent of the United States, No. 1,869,604, granted to William C. McWhirter on August 2, 1932, for Buffing devices for railway switches and the like. It is believed, therefore, that for the purposes of the present disclosure the following brief description of the buffing device D will suffice. This buffing device includes, in addition to the piston rod 50, a cam shaft 51 extending into the case of the device and controlling a valve mechanism not shown. Attached to the outer end of the cam shaft 51 is a crank 52 which is connected by a link 53 with the spring rod 14 of the spring connecting rod C. If, when the movable rails 2 and 2^a of the switch A are in their normal positions, as shown in Fig. 1, they are moved to their reverse positions by the mechanism B, the piston rod 50 will be moved into the device, and the cam shaft 51 will be rotated in a clockwise direction, as viewed from the left in Fig. 1. The construction of the device is such that, under these conditions, the piston rod 50 will be permitted to move with substantially no resistance, and the buffing device will therefore exert practically no retarding action on the rails. Conversely, if the movable rails are moved from their reverse positions to their normal positions by the mechanism B, the piston rod 50 will be moved outwardly and the cam shaft 51 will be rotated in a counter-clockwise direction, as viewed from the left in Fig. 1, but due to the construction of the device, no retarding action will again take place. If, however, when the movable rails are in either extreme position, a train trails the switch, the cam shaft 51 will remain stationary, and, under these conditions, the action of the device is such that the movement of the movable rails away from the positions which they previously occupied will be unresisted by the buffing device, but that, when the movable rails are being restored to the positions which they previously occupied, by the spring 15 of the spring connecting rod C, the buffing device will act to retard this latter movement.

The switch operating mechanism B is mounted on one end of a tie strap 18 which is secured to the ties adjacent the outer side of the rail 1, and, as best seen in Figs. 3 and 4, this mechanism, in the form here shown, comprises a main casing 19 provided with a tail-like projection 19^a, and an auxiliary casing 20 which is secured to the tail-like projection 19^a of the main casing 19. The upper end of the main casing 19 is closed by a cover 21 and a guard 22, which cover and guard are removably secured to the casing by means of studs 23, while the auxiliary casing 20 is closed by a hinged cover 24.

Formed in the main casing 19 is an axially extending rectangular guideway 25 which slidably receives a motion plate 26. The motion plate 26 is provided on its upper face with rack teeth 27, and on its lower face with a cam slot 28, and is adapted to be reciprocated between two extreme positions by means of a hand-throw lever 30 fixed to a shaft 31. The shaft 31 is journaled in suitable bearings 32 secured to the casing 19, and has fixed thereto a segment gear 33 which meshes with the rack teeth 27. As best seen in Fig. 3, the cam slot 28 is formed with a portion at each end which is parallel to the direction of movement of the motion plate, and with an intermediate con-

necting portion which is disposed at an angle to the direction of movement of the motion plate. Extending into the cam slot 28 and co-operating therewith is a roller 34 which is mounted on a pin 35 secured to an arm 36 forming part of a crank 37. The crank 37 is journaled in a vertical bearing 38 provided in the bottom of the casing 19 and has fixed thereto on the underside of the casing, a removable switch operating arm 37^a which is pivotally attached to the free end of the operating rod 9.

Reciprocably mounted in the casing 19 directly above the motion plate 26 is a locking device 39 comprising two spaced parallel side members 39^a and 39^b connected together at their opposite ends by means of integral end members 39^c and 39^d. The left-hand end member 39^c carries a rectangular locking plunger 39^e, and is formed with two spaced threaded holes 39^f and 39^g, while the other end member 39^d is provided with three unthreaded holes 39^h, 39ⁱ, and 39^k, two of which holes, 39^h and 39^k align, respectively, with the threaded holes 39^f and 39^g. The locking plunger 39^e projects with some clearance into a longitudinally extending rectangular slot 44 provided in the tail-like projection 19^a of the casing 19, and cooperates at its inner end with a lock rod L which is slidably mounted in a transverse slot 45 formed in the tail-like projection 19^a. The lock rod L, in the form here shown, is of standard construction, and comprises two longitudinally adjustable bars 46 and 47 attached at one end to the front rod 5 of the switch A, and provided with registering notches 48 (see Fig. 5), so disposed that these notches will align with the locking plunger 39^e when and only when the switch A occupies the extreme position in which it is shown in Fig. 1. The locking device 39 also comprises two bolt members 39^l and 39^m which pass through the holes 39^h and 39^k, respectively, and are screwed into the threaded holes 39^f and 39^g. These bolt members also extend with some clearance through holes 40 and 41 formed in lugs 42 and 43 secured to the upper face of the motion plate 26, and surrounding each bolt member between the associated lug 42 or 43 and the end member 39^c is a compressed coil spring 39ⁿ which biases the locking device 39 in the direction to cause the locking plunger 39^e to enter the notches 48 in the lock rod L.

Vertical displacement of the locking device 39 and the motion plate 26 are prevented by a hold-down member 114 (see Fig. 8) which hold-down member is bolted to the side of the casing 19, and which is provided on its underside near its ends with hold-down surfaces 114^a and 114^b which are adapted to slidably engage the upper edges of the side members 39^a and 39^b respectively, of the locking device 39.

For reasons which will become apparent as the description proceeds, the parts of the locking device 39 are so proportioned that when the motion plate 26 is in its left-hand or normal extreme position as shown in Fig. 1, the biasing spring 39ⁿ will tend to drive the locking device to an extreme position which is beyond the desired locking position. The locking device is prevented from moving beyond the desired locking position, under these conditions however, by linkage which connects the locking device with the tie rod 8. As here shown, this linkage includes a plunger bolt 54 which extends with some clearance through the hole 39ⁱ in the end

member 39^d, and the head of which bolt engages the left-hand side of the end member 39^d, as viewed in Figs. 3 and 4. The threaded end of the plunger bolt 39^d is adjustably connected by means of a turn buckle 55 (see Fig. 1) with one end of a link 56, the opposite end of which link is pivotally connected with the long arm 57^a of a bell crank lever 57. The bell crank lever 57 is pivotally supported in a crank stand 58, and has its short arm 57^b pivotally connected with one end of an operating rod 59. The other end of the operating rod 59 is connected with the previously described tie rod 8 by means of a standard switch basket 60. The tie rod 8 may be located at any suitable location, but will preferably be located approximately half-way between the heel and the point of the switch. The base 61 of the crank stand 58 is secured both to a gauge plate 62 and to the tie strap 18 upon which the mechanism B is mounted, and it will be apparent, therefore, that any loss of adjustment between the parts due to creepage of the ties is prevented. The plunger bolt 54, turn buckle 55, link 56, bell crank lever 57, operating rod 59, spring basket 60, and tie rod 8, also constitute means for effecting the unlocking of the switch points during a trailing move, as will be made clear presently.

The operation, as a whole, of the portion of the apparatus thus far described is as follows: When the hand-throw lever 30 occupies the extreme position in which it is shown in full lines in Figs. 1 and 3, the motion plate 26 is held in its extreme left-hand or normal position as viewed in Figs. 3 and 4, and the roller 34 on the crank 37 then occupies the right-hand end of the cam slot 28 in the motion plate, so that the crank 37 is held at the extreme end of its stroke in a clockwise direction, as viewed in Figs. 1 and 3. When the crank 37 occupies this extreme position, a force is exerted on the movable rails 2 and 2^a of the switch through the medium of the operating rod 9, spring rod 14, nut 17, sleeve 13, spring 15, housing 10, and the head rod 6, which force holds the movable rails in their normal extreme positions in which they are shown in Fig. 1. When the movable rails are in their normal positions, the notches 48 in the lock rod L align with the locking plunger 39^e, and the locking device 39 is therefore moved by the biasing springs 39^a to its locking position in which the locking plunger partly enters the registering notches 48, thus securely locking the switch points in their normal positions.

When it is desired to reverse the switch, the hand-throw lever 30 is rotated from the extreme position in which it is shown in full lines in Fig. 1, to its opposite extreme or dotted line position. This movement of the lever causes the motion plate 26 to move from its extreme left-hand position, as viewed in Figs. 3 and 4, to its extreme right-hand position. As soon as the motion plate has moved a short distance, the lugs 42 and 43 carried thereby engage the left-hand side of the end member 39^d of the locking device 39, and as a result, as the motion plate continues to move, the locking device is moved with the motion plate, thus withdrawing the locking plunger from engagement with the notches 48 in the lock rod L, and hence unlocking the movable rails 2 and 2^a. The parts are so proportioned that while the locking plunger 39^e is being withdrawn from engagement with the notches 48 in the lock rod, the cam slot 28 in the motion plate will continue to engage the roller 34 on the crank 37 at that portion of the slot at its right-hand end which is

parallel to the direction of movement of the motion plate, and as long as this portion of the slot is engaging the roller, the crank 37 will remain stationary. It follows, therefore, that during that portion of the movement of the motion plate which is necessary to unlock the movable rails of the switch, no force is exerted on these rails tending to reverse them. As soon, however, as this first part of the movement of the motion plate has been completed, the roller 34 is then engaged by the curved portion of the cam slot 28 which causes the crank 37 to be rotated in a counter-clockwise direction, as viewed in Fig. 3, and as a result, the rails are then moved to their reverse positions. As previously pointed out, when the rails are moved to their reverse positions by the mechanism B, the piston rod 50 of the buffering device D is moved into the device, and the cam shaft 51 is rotated in a clockwise direction, as viewed from the left in Fig. 1, but due to the construction of this device, the device offers substantially no resistance to the movement of the rails under these conditions. It should be noted that as long as the movable rails remain stationary, the plunger bolt 54 remains fixed, so that during the first part of the movement of the motion plate, the end member 39^d of the locking device 39 will move out of engagement with the head of the plunger bolt. As soon as the movable rails have started to move, however, the resultant movement of the tie rod 8 acting through the switch basket 60, operating rod 59, bell crank lever 57, and link 56 causes the plunger bolt to move in the same direction as the motion plate is moving, although the time of motion and rate of motion of the plunger bolt will bear no direct relation to the movement of the motion plate. During the final movement of the motion plate, the portion of the cam slot 28 in the motion plate at the right-hand end of the slot which is parallel to the direction of movement of the motion plate engages the roller 34, which prevents further rotation of the crank 37, thus locking the movable rails in their reverse positions.

In order to restore the movable rails to their normal positions after they have been reversed as above described, the lever 30 is restored to the position in which it is shown in full lines in the drawing. The subsequent movements of the parts under these conditions are just the reverse of those described above, and it is believed, therefore, that the operation of the apparatus under these conditions, will be readily understood from an inspection of the drawings without further description.

I will now assume that the parts are in their normal positions, as shown in the drawings, and that a train trails the switch. As the leading wheels of the train roll along the fixed rail 1 and the movable rail 2^a, the movable rails 2 and 2^a are forced over laterally, but, before a sufficient force is developed to overcome the opposing force of the spring 15 of the spring connecting rod C and cause the point of the movable rail 2 to move out of engagement with fixed rail 1, the movable rails being somewhat resilient become bent, so that, with the usual standard split switch, the tie rod 8 is moved upwardly, as viewed in Fig. 1, three-quarters of an inch or more. This movement of the tie rod acting through the switch basket 60, operating rod 59, bell crank lever 57, link 56, and plunger bolt 59 moves the locking device 39 in opposition to the bias of the springs 39^a a sufficient amount to withdraw the locking plunger 39^e completely out of engagement with the notches 48.

48 in the lock rod L, thus unlocking the switch. As a result, when the leading wheels have reached the position in which a sufficient force is developed to cause the point of the movable rail 2 to move 5 out of engagement with the fixed rail 1, the switch points will be unlocked, and the points will therefore be forced open by the wheels in exactly the same manner as would be the case if no facing point lock were provided, and the buffing device 10 D will perform its usual function of preventing the movable rails from snapping back after the passage of each wheel through them. When the train which is trailing the switch has completely passed the switch, the movable rails will slowly 15 return to their normal positions under the bias of the spring 15 of the spring connecting rod C, and against the retarding force of the buffing device D. During this return movement of the movable rails there will be no deflection of these rails, and 20 the locking plunger 39^a will be moved into engagement with the lock rod L before the movable rails have reached their full normal positions in which the lock rod is in the proper position for the notches 48 therein to receive the locking plunger. 25 The spring 39^a will therefore become compressed, and will urge the locking plunger 39^a into engagement with the side of the lock rod, until the notches 48 move into alignment with the locking plunger, at which time the energy stored in the 30 compressed springs 39^a will force the locking plunger into place in the notches, thus restoring the switch to its normal locked condition. If the notches 48 in the lock rod should not come into alignment with the locking plunger, a suitable 35 indication of this fact will be given by means of a circuit controller E embodying my present invention which circuit controller I will describe presently.

During a facing point move, there is no lateral 40 thrust on the movable rails corresponding to, or commensurate with, that which occurs during a trailing movement and what lateral thrust there is will be in the direction to permit the springs 39^a to force the locking plunger further into the 45 notches 48 in the lock rod L.

It will be noted that when the parts are in their 50 normal positions as shown in Fig. 1, the reaction of the biasing springs 39^a is transmitted through the rack teeth 27 and segment gear 33 to the switch-throw lever 30, which tends to raise this 55 lever. However, this lever is so designed that it has sufficient weight to resist and overcome this reaction. Furthermore, if it is undesirable for any reason to provide the lever 30 with sufficient weight to overcome the reaction of the springs 39^a, this lever may be held down by a conventional gravity lever latch stand, two of which stands are indicated at 91 in Fig. 1.

It will also be noted that when the parts are in 60 their normal position as shown in Fig. 1, since the springs 39^a tend to drive the locking device to an extreme position which is beyond its normal locking position, but are prevented from doing so by the linkage connecting the locking device 65 with the tie rod 8, these springs will cause a force to be exerted on the movable rails at the point where the tie rod 8 is connected with the rails, and this force which, due to the mechanical advantage afforded by the bell crank lever 57, is 70 relatively large, aids the force exerted by the spring 15 of the spring connecting rod in restoring the movable rails to their proper positions after the switch has been trailed, or after the switch 75 has been operated to its normal position by the hand lever. In most switch layouts when the

movable rails are in their proper normal positions, the entire length of the movable rail 2 between the tip of the rail and the point where the tie rod 8 is connected with the rail, will be in contact with the stock rail 1, and in those switch layouts 5 where this is not the case, fixed stops will usually be provided for the movable rail 2 at the point where the tie rod 8 is connected with this rail. It will be seen therefore, that with apparatus embodying my invention, when the movable rails 10 are in their proper normal positions, the movable rail 2 at the point at which the tie rod 8 is attached to this rail will be constantly urged into engagement with a definite stop by a relatively large force, thus insuring that as long as the linkage 15 connecting the tie rod 8 with the locking device is in proper adjustment, and the lock rod L is in proper working order, the locking device will always return to its proper locking position after the switch has been trailed, and will thereafter 20 remain in its proper locking position until the switch is again trailed, or until the switch is moved away from its normal position by the mechanism B.

The circuit controller E referred to herein- 25 before is located wholly within the casing 20, and in the form here shown, comprises a rocker arm 66 pivotally supported intermediate its ends on a pin 67 (see Fig. 5) secured within a pair of spaced lugs 68 extending upwardly from the bottom of 30 the casing 20. The rocker arm 66 is disposed directly above the locking plunger 39^a, and is provided with a cam slot 69 which cooperates with a roller 70 mounted in the upper end of a U-shaped bracket 71. The bracket 71 extends downwardly with considerable clearance through a longitudinal slot provided in the bottom of the casing 20 and is secured at its lower end to the locking plunger 39^a. It will be seen, therefore, that the roller 70 will be reciprocated in response to 40 reciprocation of the locking plunger 39^a. The rocker arm 66 is also provided with a cam face 74 which joins the cam slot 69 at the right-hand end of the slot, and which also cooperates with the roller 70 in a manner which will be described 45 hereinafter.

The inner end of the cam slot 69 is radially disposed with respect to the pivotal axis of the rocker arm 66, but the outer end of this cam slot is provided with an offset portion which extends 50 above the rest of the slot. The radius of curvature of this offset portion is only a little larger than the radius of curvature of the roller 70, and the parts are so proportioned that there will be only a small amount of clearance between the 55 roller and the top and bottom of the cam slot in any position of the roller within the slot. The parts are further so proportioned that when the locking plunger 39^a occupies its normal locking position, the roller 70 will engage the cam slot at 60 the central part of the offset portion. It will be apparent, therefore, that when the switch is properly locked in its normal extreme position, the rocker arm 66 will have been positively rotated in a clockwise direction to an extreme position which I shall term its "normal" extreme position. If, however, the locking plunger 39^a is moved beyond its normal locking position by the biasing springs 39^a for any reason, such for example as would be the case if excess lost motion 65 developed in the linkage connecting the locking device 39 with the tie rod 8, or if the parts were improperly adjusted, the roller 70 would be forced out of the offset portion of the cam slot, and into the radial portion, which would rotate the rocker 70 75

arm in a counter-clockwise direction from its normal extreme position to another extreme position. Furthermore, when the locking plunger 39° is withdrawn from the notches 48 in the lock rod L, the roller 70 will likewise be forced out of the offset portion of the cam slot, but under these conditions it will move into engagement with the cam face 74, thus rotating the rocker arm from its normal extreme position to its counter-clockwise extreme position. It should be noted that, due to the relatively small radius of curvature of the offset portion of the cam slot, this latter rotation of the rocker arm will take place before the locking plunger 39° has been moved far enough to clear the notches in the lock rod. The cam face 74 is so designed and the parts are so proportioned that after the roller 70 has moved into engagement with the cam face 74, no further rotation of the rocker arm will take place until the locking plunger 39° is subsequently restored to its normal locking position, at which time the roller 70 will engage the lower face 69° of the cam slot 69 and will positively restore the rocker arm to its normal extreme position.

Pivots attached to the left-hand end of the rocker arm 66 is a contact operating member 75. This contact operating member is mounted to move vertically on studs 76 which project upwardly from the bottom of the casing 20, and which pass freely through holes 75° in the operating member. Secured to the upper side of the operating member 75 are two superposed insulating blocks 78 and 79 between which are clamped the free ends of a plurality of flexible contact fingers 80, here shown as four in number. Each contact finger 80 cooperates with an associated contact member 81 to form a plunger lock contact 80—81. Each contact finger 80 and the associated contact member 81 are clamped to the opposite sides of an insulating block 82 by means of terminal posts 83 and 84, and the insulating block 82, in turn, is supported on lugs 85 projecting inwardly from the sides of the housing 20. Each terminal post 84 is electrically connected with the associated contact member 81, but is insulated from the associated contact finger 80 as will be apparent from an inspection of the drawing, while each terminal post 83 is insulated from both the associated contact finger 80 and contact member 81. The parts are so proportioned that when the rocker arm 66 occupies its normal extreme position in which it is shown in the drawing, each plunger lock contact 80—81 will be closed, but that, when the rocker arm is rotated to its other extreme position, each contact 80—81 will then become opened. It will be apparent, therefore, that the plunger lock contacts will be closed when and only when the locking plunger 39° occupies its normal locking position.

Associated with each plunger lock contact 80—81 is a point detector contact comprising a flexible contact finger 86 which cooperates with a fixed contact member 87. Each contact finger 86 is fastened at one end to a conducting strip 88, the other end of which strip is clamped against the fixed end of the associated finger 80 to make electrical contact therewith; while each contact member 87 is secured to, and electrically connected with, the associated terminal post 83.

Pivots mounted below the contact fingers 86 is a second contact operating member 89 (see Figs. 5 and 6) carrying a roller 90 which at times enters a notch 91 in a point detector rod 63. The point detector rod 63 is slidably mounted in the casing 20 and as shown in Fig. 1 is attached, by means of a link 64 and a bolt member 65 to the movable rail 2 of the switch A in the usual and well-known manner. The operating member 89 also carries an insulating strip 92 which cooperates with the movable contact fingers 86 in such manner that when the roller 90 is within the notch 91 in the point detector rod 63, the insulating strip 92 will be clear of the movable contact fingers 86, so that the contacts 86—87 will then be closed, but that, when the roller 90 is forced out of the notch 91, this strip will engage the underside of the fingers 86 and raise them to the positions in which they are out of engagement with the associated fixed contact members 87, thus opening the contacts 86—87. The notch 91 in the point detector rod 63 is so disposed and the parts are so proportioned that the roller 90 will enter the notch 91 when and only when the movable rails 2 and 2° of the switch A occupy their normal extreme positions, and the rail 2 is in proper engagement with the fixed rail 1.

As is well understood, the contacts of a circuit controller of the type described are utilized to control signals governing traffic over the switch, and their primary purpose is to cause the signal to indicate "stop" unless the switch points occupy their proper positions relative to the fixed rails and are properly locked in these positions. With the portion of the circuit controller thus far described, these contacts will adequately do this in all instances where the apparatus is in proper working order. However, if due to some failure of the operating mechanism, the locking plunger 39° does not become completely withdrawn from the notches 48 in the lock rod L in the normal manner while a train is trailing the switch, a dangerous condition might possibly exist, because under these conditions, while the switch points will be displaced at the top an amount which would easily operate the point detector contacts of the circuit controller if the detector rod could be connected with the points at the top of the points, it is necessary for clearance reasons to connect the detector rod to the switch points some distance below the top of the points, where, due to the rolling of the points during the trailing, the amount of the movement may not be more than one-half of that occurring at the top of the points; and furthermore, after a train has trailed the switch, the points will usually spring back toward their original positions a certain amount. As a result, the final displacement of the point detector rod may be very little, if any, more than the displacement which would correspond to a maximum permissible opening of the closed switch point, which is the setting at which the point detector contacts become opened, while the opening of the closed point at the top might be sufficient to be extremely dangerous for subsequent high speed train movements. In order to insure that this dangerous condition will be detected, I provide a latching mechanism so constructed that if the switch fails to become unlocked while the train is trailing the switch, this latching mechanism will retain the indication contacts in their operated positions until they are subsequently released by a maintainer. Thus, even though the switch points spring back toward their proper positions after the train has trailed through the switch, the signals governing traffic over the switch will continue to display a restrictive indication until the maintainer releases the contacts of the circuit controller and permits them to return to their normal positions. It is assumed that before the maintainer does this,

he will inspect the switch points, and, if damaged, repair them, thus guarding against a dangerous condition due to damaged switch parts.

Referring now again to Figs. 3 and 4, the latching mechanism just referred to comprises a latch arm 107 which is secured at its left-hand end to the contact operating member 89, and which extends toward the right from the pivotal axis of this operating member. A latch dog 106 is provided on the extreme right-hand end of the latch arm 107, and cooperating with this latch dog is a latch catch 100 having a screw threaded upper portion 100^a which is adjustably screwed through a tapped hole 95^a in a latching member 95. The latch catch is also provided with a rectangular latch head 100^b having its opposite sides cut away to form two notches 104 and 105, and the latch catch is adapted to be locked, by means of a lock washer 101 and a jam nut 102 provided on the threaded portion 100^a above the latching member 95, in an adjusted position in which either the side of the latch head 100^b containing the notch 104, or the opposite side, faces the latch dog. To facilitate adjusting the latching member, the upper end of the threaded portion 100^a is provided with a saw kerf 100^c for the reception of a screw driver.

The latching member 95 extends transversely of the casing 20 directly above the left-hand end of the rocker arm 66, and is pivotally supported at its ends on trunnion screws 96 which are adjustably mounted in bosses 97 formed in the side walls of the casing 20. A substantially horizontal cam arm 108 extends toward the right from the latching member 95 and is provided adjacent its right-hand end with two converging downwardly extending cam faces 111 and 112 which cooperate, under certain conditions later to be described, with the roller 70 carried by the locking plunger 39^e. The cam arm 108 also serves to overbalance the latching member, so that the latching member tends to constantly rotate in a clockwise direction about the trunnion screws.

The latching member 95 is further provided with a depending leg 109 (see Fig. 7) carrying a horizontal latching foot 110 which extends underneath the rocker arm 66. The latching foot 110 coacts with the lower end of a latching plunger 113 which extends upwardly through concentric holes 114 and 115 (see Fig. 5) formed in an upwardly projecting portion provided in the left-hand end of the rocker arm 66. The hole 114 is made considerably larger in diameter than the hole 115 since hole 114 is adapted for the reception of a coil spring 116 which surrounds the latching plunger 113 between the upper end of the hole 114 and a guide 117 which is secured to the plunger. The spring 116 biases the latching plunger to a lowermost position in which it is stopped by a nut 118 screwed onto the upper end of the latching plunger above the hole 115.

The parts of the latching mechanism are so proportioned, and the latch catch 100 is so adjusted that when the roller 90 on the contact operating member 89 is within the notch 91 in the point detector rod 63, and the locking plunger 39^e is within the notches 48 in the locking rod L, as shown in the drawings, the latch head 100^b of the latch catch 100 will engage the end of the latching dog 106 on the latch arm 107 just above the notch 104, and will thus prevent the latching member from rotating in a clockwise direction past the position in which it is shown in the drawings. In order to prevent vibration and consequently wear between the latch catch and the

latching dog due to the passage of trains over the switch when the parts are in these positions, a spring 119 is stretched between a depending lug 120 on the operating member 89, and a lug 121 formed on the side of the leg 109 of the latch member. It will be seen that this spring increases the normal tendency of the latching member to rotate in a clockwise direction, and the tendency of the operating member 89 to rotate in a counter-clockwise direction, so that the latch catch is normally held firmly against the end of the latching dog, and the latching dog is prevented from vibrating up and down.

In explaining the operation of the circuit controller as a whole, I will first assume that the switch points are locked in their normal positions and that a train trails the switch. I will also assume that while the train is trailing the switch, the locking mechanism functions in the manner previously described so that the locking plunger 39^e becomes fully withdrawn from the notches 48 in the lock rod L and unlocks the switch points before the switch points are forced open by the wheels of the train, and that after the train has completely trailed the switch and the switch points have been returned to their normal positions by the spring 15 of the spring connecting rod C, the locking plunger is restored to its normal locking position to relock the switch points in their normal positions. Under these conditions, as soon as the locking plunger 39^e starts to move toward its unlocking position due to engagement of the wheels of the train with the movable rails of the switch, roller 70 will rotate rocker arm 66 in a counter-clockwise direction from its normal extreme position to its other extreme position in the manner previously described, and this rotation of the rocker arm will open the plunger lock contacts. This rotation of the rocker arm will also cause the latching plunger 113 to move into engagement with the upper side of the latching foot 110, thus forcing the latching plunger upwardly in opposition to the bias of spring 116. When the locking plunger 39^e reaches the position where it is just clear of the lock rod L, roller 70 will move into engagement with cam face 111 of cam arm 108, and as the latching plunger continues its movement, cam arm 108 will be rotated in a counter-clockwise direction by the roller 70. This rotation of the cam arm, in turn, will rotate the latching member 95 to a position in which the latch catch 100 is out of engagement with latching dog 106, and in which the latching foot 110 is clear of the right-hand side of the latching plunger 113. As soon as the latching foot 110 clears the latching plunger, the spring 113 will force the latching plunger to its lowermost position, and as a result, when the roller 70 has moved completely past the cam face 111 on the cam arm 108, the latching plunger 113 will engage the latching foot 110 at the left-hand side of the latching foot and will thus hold the latching member 95 substantially in the extreme position to which it was previously moved by the roller 70. When the switch points are next forced open by the trailing train, the roller 90 on the contact member 89 will be forced out of the notch 91 in the point detector rod, which action will rotate the operating member 89 to the position in which the point detector contacts 86-87 become opened. The parts will then remain in the positions which they then occupy until the train has completely trailed the switch and the switch points have started to return to their normal positions. When this hap-

pens, the locking plunger will, of course, start to return to its normal locking position, and during the first part of this return movement, the roller 70 will engage the cam face 112 on the cam arm 108, and will raise the cam arm 108 slightly, so that the latching member 95 will be rotated through a small angle in a counter-clockwise direction from the position where it is stopped by engagement of the latching plunger 113 with the left-hand side of the latching foot 110. As soon, however, as the roller 70 has moved past the cam face 112, the latching member will return by gravity to its "latched" position. Shortly after the roller 70 passes the cam face 112, the end 15 of the locking plunger 39^a will move into engagement with the side of the lock rod L, but no further operation of the apparatus will take place until the switch points have been returned toward their normal positions far enough so that the notch 91 in the point detector rod 63 aligns with the roller 90, at which time the roller 90 will enter the notch 91. When this happens, the point detector contacts will close and the latch arm 107 will be restored to its normal position in 20 which it is shown in the drawings. When the switch points reach their full normal position, the notches 48 in the lock rod L will then align with the locking plunger and will allow the locking plunger to snap into its normal locking position under the action of the biasing springs 39^a in the manner previously described. As the locking plunger thus completes its return stroke, roller 70 will engage cam surface 69^a of cam slot 69 in rocker arm 66, and will thus rotate the rocker arm to its normal position. This rotation 25 of the rocker arm, in turn, will cause the plunger lock contacts 80—81 to close, and will also raise the locking plunger 113 to the position in which it is out of engagement with the latching foot 110. As soon as the latching plunger has moved 30 out of engagement with the latch foot, the latching member 95 will return, under the influence of gravity and the bias of the spring 119, to the position in which the latch catch 100 engages the end of the latching dog 106, and all parts of the circuit controller will then be restored to their 35 normal positions in which they are shown in the drawings.

Where the parts are in the positions in which they are shown in the drawings, and the switch is operated to its reverse position by means of the hand-throw lever 30, the operation of the circuit controller will be similar to that just described for a trailing movement up to the point where the switch points start to return to their normal positions. Likewise, after the switch points have been moved to their reverse positions by the hand-throw lever, and the hand-throw lever is subsequently operated to restore the switch points to their normal positions, the operation of the circuit controller will be similar to that just described for a trailing movement from the point where the switch points have started to return to their normal positions.

I will now assume that a train trails the switch, and that the mechanism is so far out of adjustment that the locking plunger remains in its normal locking position during the entire time the train is trailing the switch. Under these conditions, the plunger lock contacts 80—81 will remain closed, but due to the extreme forces which are exerted on the switch points by the trailing train, the point detector rod will be moved upwardly as viewed in Fig. 2 far enough to cause the roller 90 on the contact operating

member 89 to move out of the notch 91 in the lock rod L. As a result, the operating member 89 will be rotated to the position in which the point detector contacts become opened, and in which the latch dog 106 on the latch arm 107 aligns with the notch 104 in the latch catch 100. The latching member 95 will therefore now rotate, due to its bias, to the position in which the latch dog 106 enters the notch 104 in the latch catch 100. It will be apparent from an inspection of the drawings that when the latch dog 106 has once entered the notch 104 in the latch catch 100, the operating member 89 will be held in the position in which the point detector contacts are open until the latch catch is subsequently moved out of engagement with the latch dog even if the point detector rod subsequently returns to the position in which the notch 91 aligns with the roller 90. It follows that in order to release the operating member and permit the point detector contacts to become closed after they have once been opened in the manner just described, it is necessary to restore the latching member 95 to its normal position in which it is shown in the drawings. This may be done either by removing the hinged cover 24 from the casing 20 and raising the cam arm 108 manually, or by throwing the switch movement by hand to its reverse position, in which latter case, roller 70 will raise the cam arm and thus release the operating member. When the point detector contacts are released by throwing the switch movement to its reverse position by hand, if the switch points have been distorted at all by the trailing train, the locking plunger will not reenter the lock rod 30 when the switch is subsequently restored to its normal position, because the distortion of the switch points will cause the lock rod to be out of adjustment, and as a result, the plunger lock contacts will remain open, thus insuring that an indication of the damaged condition of the switch will be given.

If, when a train trails the switch, the locking mechanism is only partly out of adjustment so that the locking plunger is partly withdrawn from engagement with the notches 48 in the lock rod L but is not moved far enough to clear the notches, the apparatus will still operate to latch the point detector contacts open until they are subsequently manually released. Under these 45 conditions, the operation of the mechanism will be the same as that just described with the exception that the rocker arm 66 will now be rotated from its normal extreme position to its other extreme position, so that the latching plunger 113 will be moved upwardly by engagement of the latching plunger with the latching foot 110. This engagement of the latching plunger with the latching foot 110 will not prevent the latching device from rotating to its latching position, as might appear on first thought, but on the contrary, the end of the latching plunger and the top of the latching foot are disposed at such an angle as to tend to urge the latching member 95 toward its latching position. It will be seen, therefore, that when the switch points are forced open, thus rotating the operating member 89 in a clockwise direction to the position in which the point detector contacts are forced open, the latching member 95 will be rotated to the position in which the latch dog 106 enters the notch 104 in exactly the same manner as it was rotated when the plunger remained in its normal latching position. When the latching member has been rotated to the po- 50 55 60 65 70 75

sition in which the latch dog 106 enters the notch 104 in the latch catch 100, the point detector contacts will then be held open until the latching member is subsequently restored to its normal position in the manner previously described.

5 Although I have herein shown and described only one form of circuit controllers embodying my invention, it is understood that various changes and modifications may be made therein 10 within the scope of the appended claims without departing from the spirit and scope of my invention.

Having thus described my invention, what I claim is:

15 1. In combination, a spring switch, a lock rod connected with the switch and provided with a notch, a locking plunger biased to a position in which it will enter the notch in said lock rod when and only when the switch occupies one extreme position, means for at times withdrawing said locking plunger from said notch to unlock said switch, a contact, means for operating said contact when said switch is moved away from said one extreme position, and means for latching said contact in its operated position if and only if the movement of the contact to its operated position is due to the switch being moved away from said one extreme position by a train 20 trailing the switch while the switch is locked in said one extreme position.

25 2. In combination, a spring switch, a lock rod connected with the switch points to move therewith and provided with a notch, a locking plunger, means for at times moving said locking plunger into the notch in said lock rod to lock the switch points in one extreme position and for at other times withdrawing said locking plunger from said notch to unlock the switch points, a normally closed contact, means effective 30 if the switch points are moved away from said one position when said locking plunger is within said notch for latching said contact open, and means effective upon withdrawal of said locking plunger from the notch in said lock rod after said 35 contact has been latched open for unlatching said contact.

40 3. In combination, a spring switch, a lock rod connected to the switch points to move therewith, a locking plunger movable between a locking and an unlocking position and effective when in its locking position for engaging said lock rod to lock said switch in its normal position, means for moving said locking plunger between its locking and unlocking positions, a contact operating 45 member movable between two positions and biased to one position, means for moving said contact operating member from its one position to its other position whenever said switch occupies any position but its normal position, a contact 50 controlled by said contact operating member, and means for latching said contact operating member in its other position if said contact operating member is moved to its other position when said locking plunger occupies its locking 55 position.

45 4. In combination, a spring switch, a lock rod connected to the switch points to move therewith, a locking plunger movable between a locking and an unlocking position and effective when 60 in its locking position for engaging said lock rod to lock said switch in its normal position, means for moving said locking plunger between its locking and unlocking positions, a contact operating member movable between two positions and biased to one position, means for moving 65 said contact operating member from its one position to its other position whenever said switch occupies any position but its normal position, a contact controlled by said contact operating member, a latch arm secured to said contact operating member and provided with a latch dog, a latch catch biased to one position and movable to said one position 70 when and only when said operating member 75

5 said contact operating member from its one position to its other position whenever said switch occupies any position but its normal position, a contact controlled by said contact operating member, means for at times latching said contact operating member in its other position when said contact operating member is moved to its other position, and means for rendering said latching means ineffective when said locking plunger occupies its locking position.

10 5. In combination, a spring switch, a lock rod connected to the switch points to move therewith and provided with a notch, a locking plunger movable into and out of engagement with said notch when and only when the switch occupies its extreme normal position, means for moving said locking plunger into and out of engagement with said notch, a contact operating member movable between two positions and biased to one position, means for moving said contact operating member from its one position to its other position whenever said switch occupies any position but its normal position, a contact controlled by said contact operating member, means for at times latching said contact operating member in its other position, and means for rendering said latching means ineffective except when said locking plunger is in engagement with said notch in said lock rod.

15 6. In combination, a spring switch, a lock rod connected with the switch points to move therewith and provided with a notch, a locking plunger, means effective when said switch occupies its normal position for biasing said locking plunger to a locking position in which it enters the notch in said lock rod, means for at times moving said locking plunger to an unlocking position in which the plunger is withdrawn from the notch in said lock rod, a pivoted contact operating member biased to one position and provided with a roller, a point detector rod connected with the normally closed switch point and provided with a notch which is adapted to receive said roller when and only when said switch occupies its normal position, a contact controlled by said contact operating member, and latching mechanism controlled in part by said locking plunger and cooperating with said contact operating member in such manner that if said roller is forced out of the notch in said point detector 20 rod while said locking plunger is within the notch in said lock rod, said contact operating member will subsequently be held in the position in which the roller is out of the notch in the point detector rod until the latching mechanism 25 is operated to release the contact operating member.

30 7. In combination, a spring switch, a lock rod connected to the switch points to move therewith and provided with a notch, a locking plunger movable into and out of engagement with said notch, a contact operating member movable between two positions and biased to one position, means for moving said contact operating member from its one position to its other position whenever said switch occupies any position but its normal position, a contact controlled by said contact operating member, a latch arm secured to said contact operating member and provided with a latch dog, a latch catch biased to one position and movable to said one position 35 when and only when said operating member 40

is moved to its other position and cooperating when in said one position with said latch dog to latch said contact operating member in its other position, and means controlled by said locking plunger for preventing said latch catch from moving to its one position whenever said locking plunger is out of engagement with the notch in said lock rod.

8. In combination, a spring switch, a lock rod connected to the switch points to move therewith and provided with a notch, a locking plunger movable into and out of engagement with said notch when and only when the switch occupies its extreme normal position, means for moving said locking plunger into and out of engagement with said notch, a contact operating member movable between two positions and biased to one position, means for moving said contact operating member from its one position to its other position whenever said switch occupies any position but its normal position, a contact controlled by said contact operating member, a latch arm secured to said contact operating member and provided with a latch dog, a pivoted latching member provided with a depending latch catch having a latch head containing a notch, means for biasing said latching member to such a position that when said contact operating member is moved to its other position said notch will receive said latch dog and latch said contact operating member in its other position, and means controlled by said locking plunger for rotating said latching member away from the position to which it is biased whenever said locking plunger is withdrawn from the notch in said lock rod.

9. In combination, a spring switch, a lock rod connected with the switch points to move therewith and provided with a notch, a locking plunger adapted to enter the notch in said lock rod when and only when the switch occupies its normal extreme position, said locking plunger being movable within said notch to an extreme position which is beyond its normal locking position, means for moving said locking plunger into and out of engagement with said notch, a roller secured to said locking plunger, a pivoted rocker arm provided with a cam slot which receives said roller, said cam slot being so designed that when said locking plunger occupies its locking

position said rocker arm will be rotated to one extreme position but that if said locking plunger is moved beyond, or is withdrawn from, its locking position said rocker arm will be rotated to another extreme position, a plunger lock contact operated by said rocker arm, a point detector rod provided with a notch, a contact operating member provided with a roller which aligns with the notch in said point detector rod when and only when the switch occupies its normal extreme position, said contact operating member being biased to a position in which the associated roller will enter the notch in said point detector rod when this roller aligns with this notch, a contact operated by said contact operating member, a pivoted latching member, a cam arm secured to said latching member and biasing said latching member to a latching position, said cam arm being provided with cam faces which cooperate with the roller secured to said locking plunger to rotate said latching member to a second position when said locking plunger is withdrawn from the notch in said lock rod, a depending leg on said latching member provided with a latching foot which extends underneath said rocker arm, a latching plunger mounted in said rocker arm and biased to one position and cooperating at its lower end with said latching foot in such manner that if said latching member is moved to its second position when said rocker arm occupies its other extreme position said latching plunger will engage said latching foot and hold said latching member in its second position until said rocker arm is subsequently returned to its one extreme position, a latch arm secured to said contact operating member and provided with a latch dog, and a latch catch secured to said latching member and provided with a latch head containing a notch which is adapted to receive said latch dog when and only when said contact operating member occupies the position in which said roller is out of the notch in said point detector rod and said latching member is rotated to its latching position, the parts being so proportioned that when said notch is receiving said latch dog said contact operating member will be held in the position in which said roller is out of the notch in said lock rod.

HERBERT L. BONE.
